UNITED STATES PATENT OFFICE.

EMMETT A. NIBLACK, OF UNITED STATES ARMY, FORT SILL, OKLAHOMA.

AUTOMATIC SPARK-RETARDING ATTACHMENT FOR INTERNAL-COMBUSTION ENGINES.

Application filed October 15, 1926. Serial No. 141,821.

(GRANTED UNDER THE ACT OF MARCH 3, 1883, 22 STAT. L., 625.)

The invention described herein may be used by the Government, or any of its officers or employees in prosecution of work for the Government, or by any other person in the United States, without payment to me of any royalty thereon.

This invention relates to motor attachments and more particularly to an automatic spark retarding attachment for internal combustion engines having electric motor starting mechanism, ordinarily used on motor vehicles.

An object of this invention is to provide a simple durable and inexpensive structure wherein means are provided for retarding the spark of a motor prior to the operation of the starter.

Another object being to prevent back-fire of the motor due to an advanced spark in starting, thereby avoiding in some instances a broken Bendix spring, a bent or broken starter motor shaft or other damage to the starter or motor parts.

A further object being to provide an arrangement of parts whereby the operation of the starter cannot be accomplished without previously operating the spark retarding mechanism and thereby avoid the operation of the starter without first retarding the spark.

30 These and other objects will appear in the following description and be finally pointed out in the appended claims.

Similar numerals indicate corresponding parts in all the figures of the drawings in which:

Fig. 1 is a side view of a fragment of a motor vehicle showing my improved spark retarding mechanism applied thereto.

Fig. 2 is a plan view of same.

40 Fig. 3 is a front view of the attachment.

Fig. 4 is a rear view line 4-4 of Fig. 2.

45 Figs. 5 and 6 are enlarged detail side and end views of the adjustable sleeve and its crank arm.

Referring to the drawings by numerals, 1 represents a conventional form of motor, 2 the dash, 3 the floor of a motor vehicle.

For purposes of illustrating an application
50 of the improved attachment, the commutator
4 is shown at the front of the motor and
through conduits not shown, is connected with

...and simple patterns of single leaf sets and branched sets of three pairs of pinnatifid leaves of which the

ENT FOR INTERNAL-COMBUSTION ENGINES

MARCH 2, 1882. 22. STAT. I. 625.)

the spark plugs of the motor in the usual

Any form of mechanism operated usually from adjacent to the starting wheel for the adjustment of the commutator and controlling the advance and retarding of the spark may be used, said mechanism not being a part of this invention and its not shown or described.

Projecting up through the floor 3 of the vehicle is the usual starter button 5, adapted when depressed to complete a circuit between the source of energy and the starter motor of any well known form of motor starter mechanism, said button only being shown in the drawings.

In starting an internal combustion motor with the spark advanced in the position it usually occupies while the motor is running at high speed and the position it is usually left in when the motor is stopped, there is great danger of a back-fire and costly damage done to the starter mechanism or motor such as a bent starter shaft, motor shaft, or the stripping of gears.

This attachment is intended to accomplish, without any consideration on the part of the operator, the automatic retarding of the spark of the motor prior to the operation of the starter by arranging the parts of the retarding mechanism in such a manner as to place the operating lever of said retarding mechanism in the path of the foot of the operator on its way to the starter button 5, thus making it impossible to operate the starter without first retarding the spark.

Rotatably supported in brackets mounted on the engine block 7 and frame 8 of the vehicle, on dash 2 and in bearing 10 mounted on a cross member 11, is the rocker shaft 12.

95
100
Mounted on the rear end of rocker shaft 12 is a crank arm 13, said arm extending laterally from the rocker shaft, and in its free end, is mounted the lower end of a short post 14 which extends up through an opening 15 in the floor of the vehicle adjacent to the starter button 5 and is provided at its upper end with a foot piece 16 extending laterally directly over the button 5.

For the purposes of illustrating this invention, a vertically slideable button 5 is shown for operating the starter, but it will be un-

derstood that the foot piece 16 will operate as effectively in combination with any of the well known depressible foot members now generally used for operating the starter mechanism and may be arranged above the depressible portion of such a member.

10 Adjustably mounted on the forward end of shaft 12 is a split sleeve 17 adapted to be clamped rigidly on the shaft by bolt 18 extending through ears 19. An adjustable crank arm 20 is clamped in the sleeve by bolt 21 and on its outer angular extension 22 of crank arm 20 is mounted one end of the commutator rod 23 which is secured thereon by 15 split pin 24. Rod 23 connects the arm 20 and the commutator or distributor arm 25 extending from the commutator 4.

The operation of the spark retarder is as follows: the operator in bringing his foot into position over the starter button to start the motor, must necessarily bring his foot down on arm 16 prior to reaching the button, said arm being depressed, shaft 12 is rotated and through rod 23, the commutator moved to the retarded spark position. When the hand lever (not shown) and its connection with the commutator is operated to advance the spark in the usual way, the parts of the retarding mechanism, will be returned to their original position.

With the above retarding mechanism arranged as described, it will be impossible to operate the starter without first retarding the spark, for the reason that the foot on its way to the starting button must first depress the foot piece 16, which will through the means shown throw the commutator to retarded position.

Having thus fully described my invention, what I claim and desire to secure by Letters 40 Patents is:

Patent is:
C1. In combination, an internal combustion motor, a starter mechanism for the motor having a foot operated starter button, and a commutator having an operating arm for controlling the spark of the motor, and a rocker shaft having a crank arm at its rear end, a foot piece arranged above the starter button, in the path of the foot of the operator, and connected with the free end of the crank arm, an adjustable sleeve mounted on the forward end of the rocker shaft, a crank arm mounted in the adjustable sleeve, and a rod connecting said last mentioned crank arm and the commutator arm all arranged to move the commutator to retarded spark position when the foot piece is depressed. 45 50 55

2. In combination, an internal combustion motor, a starter mechanism for the motor having a foot operated starter button, and a commutator having an operating arm for controlling the spark of the motor, a rocker shaft arranged longitudinally of the motor, a crank arm at the rear end of the rocker shaft, a foot piece arranged above the starter button in the path of the foot of the operator, a vertically slideable post connecting said foot piece and the free end of said crank arm, an adjustable sleeve clamped on the forward end of the rocker arm, a crank arm adjustably mounted in the sleeve, and a connecting rod between said last mentioned crank arm and the commutator arm, all arranged to move the commutator to retarded spark position, when the foot piece is depressed.

EMMETT A. NIBLACK.
